UNITED STATES PATENT OFFICE.

ELISHA H. SCOTT, OF RICHMOND, INDIANA, ASSIGNOR TO SWAYNE, ROBINSON AND CO.,
OF RICHMOND, INDIANA, A CORPORATION OF INDIANA.

FEEDING DEVICE FOR ENSILAGE-CUTTING MACHINES.

1,136,978.

Specification of Letters Patent. Patented Apr. 27, 1915.

Application filed June 5, 1913. Serial No. 771,844.

To all whom it may concern:

Be it known that I, ELISHA H. SCOTT, a citizen of the United States, residing at Richmond, in the county of Wayne and State of Indiana, have invented certain new and useful Improvements in Feeding Devices for Ensilage-Cutting Machines, of which the following is a specification, reference being had therein to the accompanying drawing.

This invention relates to feeding devices for ensilage cutting machines and the like.

The object of the invention is to provide means for exerting the desired pressure on the movable one of a pair of feeding rollers in such a manner as to secure a large amount of flexibility and to enable the roller to automatically accommodate itself to varying quantities of material and to different quantities of material on different sides of the feed-way; and further, to provide such means which will permit the pressure to be adjusted to accommodate the same to or to compensate for resistance which may be offered to one end or the other of the movable roller.

In the accompanying drawings, Figure 1 is a perspective view, partially broken away, of a portion of an ensilage cutter embodying my invention; Fig. 2 is a detail view of the weight box, and Fig. 3 is a transverse sectional view, with the feed rollers and the weight box in elevation.

In these drawings I have illustrated one embodiment of my invention and have shown the same as embodied in an ensilage cutter comprising a casing 1, in which is located a rotary cutter, not here shown.

Leading to the cutting mechanism is a feed chute 2 which is here shown as provided with a conveyer 3 which, however, may be dispensed with if desired.

Arranged at the inner end of the chute 2 and between the chute and the cutting mechanism are feeding rollers 4 and 5 which serve to feed the material to the cutting mechanism. These rollers are connected one to the other by means of gearing 6 and are positively driven in a well known manner which it is not necessary to here describe. One of the rollers, preferably the upper roller, is adjustable toward and away from the lower roller to permit it to accommodate itself to different quantities of material. In order to permit of this movement the shaft

7, by means of which the roller is connected with the gearing 6, is formed in two parts and the two parts are connected by a universal joint 8, thus permitting the rise and fall of the roller without affecting the driving operation.

It is necessary that pressure should be exerted upon the upper roller, 4, to cause it to properly act upon the material which is being fed to the cutter. Heretofore springs 35 have been used for this purpose but the throw is a long one and the spring or springs which could be used would not allow of the desired degree of flexibility and the roller would not tilt automatically to an extent necessary to cause it to feed a large quantity of material on one side of the feed-way and a relatively small quantity of material on the other side of the feed-way. Further, the driving shaft 7 which is connected to one end of the roller tends to exert a downward pull thereon and thus to increase the pressure at that end of the roller, causing the material to be fed more rapidly there than at the other end. 75 To overcome these difficulties and to secure the necessary pressure with the desired amount of flexibility I have provided means whereby weights may be utilized for this purpose. To this end guideways are formed 85 in the frame of the machine above the upper feed roller and, in the present instance, these guideways, which are shown at 9, are merely extensions of the guideways in which the bearings 10 for the respective ends of 90 the upper feed roller are mounted.

Mounted above the upper feed roller and controlled by the guideways 9 is what may be termed a weight-box 11, that is, a device adapted to support a weight or weights and connected with the upper feed roller to exert thereon the desired pressure. This weight-box is here shown as having a bottom, one side and two end walls, each end wall being provided with lugs or guides 12 100 adapted to move in the respective guideways 9. These lugs are pivotally connected at their lower ends, as shown at 13, to upwardly extending lugs or fingers 14 carried by the respective bearings for the roller.

Obviously, the shape of the supporting device and the manner of connecting the same with the roller may be varied. It will be noted, however, that all of the weight of the box is carried by the roller and that the 110

box, which is usually made of cast iron, not only has considerable weight in itself, but is capable of receiving plates or bars, as shown at 15 in Fig. 2, which will add to its weight to the desired extent. Further, it will be noted that these bars may be of different lengths or may be heavier at one end than at the other end so as to enable a greater weight to be added at one end of the roller than is added at the other end of the roller. The weights may be secured in the box in any suitable manner, but as here shown, the box is provided at each end with ribs or guides 16 to enter notches in the corresponding ends of the plate and a bolt or pin 17 extends upwardly from the bottom wall of the box and is adapted to extend through apertures formed in the plates. In this manner the weights can be very readily added to or removed from the weight box.

The operation of the device will be readily understood from the foregoing description and it will be apparent that as the upper feed roller tilts to adjust itself to different quantities of material at different ends thereof the weight box or pressure device will still maintain a working pressure upon both ends thereof. Moreover, this pressure is not only a working pressure but is substantially the normal pressure, that is to say, the manner of connecting the box with the roller is such that the pressure exerted upon the ends of the roller when the latter is tilted from the normal or horizontal position is substantially the same as is exerted upon these ends when they are in their normal positions. The importance of a construction which will maintain the working pressure upon the roller when the same is tilted from its normal position is at once obvious when it is understood that in ensilage cutting machines, which operate upon stalks of green corn, the rise and fall of the feeding roller is frequently five or six inches and that one end of the roller may be moved to substantially the full height, while the other will drop almost to its lowermost position. Unless the pressure is equalized and maintained on both ends of the roller the stalks at the lower end will either not feed at all or will feed forward irregularly, causing an unequal cut and unsatisfactory product, as well as reducing the capacity of the machine.

While I have shown and described one embodiment of my invention it will be understood that this has been chosen for the purpose of illustration only and that I do not desire to be limited to the details of construction shown and described, for obvious modifications will occur to a person skilled in the art. I further wish it to be understood that the cut-off for controlling the feed, which is shown but not described or claimed in the present application, does

not form a part of the present invention but forms the subject matter of a separate application for patent filed May 29th, 1913, Ser. No. 770,668.

Having thus fully described my invention what I claim as new and desire to secure by Letters Patent is:—

1. The combination, with a pair of feed rollers, one of which is movable toward and away from the other and is also capable of movement about a transverse horizontal axis, of a weighted pressure device movably supported above the movable feed roller and connected to the opposite ends thereof to maintain working pressure upon both ends of said roller when the latter is moved about its transverse axis. 75

2. The combination, with a pair of feed rollers, one of which is movable toward and away from the other and is also capable of movement about a transverse horizontal axis, of a weighted pressure device movably supported above the movable feed roller and connected to the opposite ends thereof to maintain substantially normal pressure upon both ends of said roller when the latter is moved about its transverse axis. 85

3. The combination, with a pair of feed rollers, one of which is movable toward and away from the other and is also capable of movement about a transverse horizontal axis, of a weighted pressure device movably supported above the movable feed roller and connected to the opposite ends thereof to maintain working pressure upon both ends of said roller when the latter is moved about its transverse axis, and means for varying the amount of said pressure. 95

4. The combination, with a pair of feed rollers, one of which is movable toward and away from the other and is also capable of movement about a transverse horizontal axis, of a weighted pressure device movably supported above the movable feed roller and pivotally connected to the opposite ends thereof on transverse axes above the axis of said roller. 105

5. The combination, with a pair of feed rollers, one of which is movable toward and away from the other and is also capable of movement about a transverse horizontal axis, of a weight box movably supported above said movable feed roller and pivotally connected to the opposite ends of said roller on axes above the axis thereof, and weights 115 removably mounted in said weight box to regulate the pressure upon said feed roller. 120

6. The combination, with a pair of feed rollers, one of which is movable toward and away from the other and is also capable of movement about a transverse horizontal axis, of a weight box movably supported above said movable feed roller and pivotally connected to the opposite ends of said roller on axes above the axis thereof, and means 125 130

to retain weights of different sizes in fixed positions in said box to regulate the pressure on different portions of said roller.

7. The combination, with a pair of feed rollers, one of which is movable toward and away from the other and is also capable of movement about a transverse horizontal axis, and a driving shaft connected to one end of said movable roller to impart rotary movement thereto and to permit of the vertical movement thereof, of a weighted pressure device supported above and connected with said movable feed roller, and means for increasing the weight of said pressure device at that end opposite the end of the roller to which said shaft is connected.

8. In a machine of the character described, the combination, with a frame member having guideways, a pair of feeding rollers mounted in said frame, bearings for one of said rollers mounted in said guideways, a finger secured to each of said bearings, a weight-supporting device having lugs at its

opposite ends extending into said guideways above said bearings, said lugs being pivotally connected to the fingers of the respective bearings.

9. The combination, with a pair of feeding rollers, one of which is movable toward and away from the other, of a weight-box movably supported above said movable feeding roller and connected to the opposite ends thereof, said weight-box comprising a bottom and end walls, said end walls having ribs on the inner faces thereof, a pin extending upwardly from the bottom of said box, and a weight having an opening to receive said pin and having notches at its ends to receive the ribs in the respective end walls of said weight-box.

In testimony whereof, I affix my signature in presence of two witnesses.

ELISHA H. SCOTT.
